UNITED STATES PATENT OFFICE.

HEINRICH MÜLLER, OF NUREMBERG, GERMANY.

TOY FIGURE WITH MOVABLE HEAD.

Application filed March 29, 1922. Serial No. 547,864.

To all whom it may concern:

Be it known that I, HEINRICH MÜLLER, a citizen of the German Republic, residing at Nuremberg, Germany, have invented certain new and useful Improvements in Toy Figures with Movable Heads, of which the following is a specification.

This invention relates to toy figures in which the head is mounted by means of a pivot pin upon a support which is pivotably arranged in the body, so that the head can be raised and lowered and further turned without any friction between the head and the body. This invention relates particularly to the special construction of the head, specially of a softly stuffed head, which permits to mount the head in a simple manner so that it can execute the above mentioned movements.

According to the invention a cup-shaped plate is arranged as bottom plate of the head, a casing, open at the lower end, being arranged upon this cup-shaped plate, the support of the head and the means for producing the movements of the head projecting into this casing.

The invention has further for its object to make from toy figures of the above mentioned type, saddle animals the head of which can be turned in any direction, raised or lowered by the child who is sitting upon the animal, whereby the illusion is produced as if the animal were alive.

In order that the invention may be clearly understood, I shall proceed to describe the same with reference to a toy elephant shown by way of example on the accompanying drawing, wherein:

Figs. 1 and 2 show a toy elephant in dash-and-dot lines, the head and tail being shown on Fig. 2 in a different position as on Fig. 1. The device for mounting the movable head and tail is shown in section.

Fig. 3 is a plan view of the head.

Figs. 4 and 5 are sections respectively on lines 4—4 and 5—5 of Fig. 1.

A cup-shaped plate 1 is fixed upon the inner end of the head 23 which is in contact with the body 22 of the toy elephant. This cup-shaped plate 1 has an oblong slit 2 upon the edges of which a casing 3 is mounted. The casing is pivotally mounted on the tubular support 5 by means of a pivot pin 4 fixed in the walls of the casing. The support 5 is attached to a cup-shaped plate 6 which closes the neck of the body and which

is concentric with the cup-shaped plate 1 of the head. The support is further guided in the rear wall 7 of a horizontal casing 8 in the body of the toy figure and it projects at the rear end of the body. The projecting end of the support 5 has two downwardly directed flaps 17 between which a lever 19 is pivotably mounted by means of a cross pin 18. A rod 11 is hingedly connected by pin 20 with the upper end of lever 19, said rod being located in the tubular support 5. The front end of rod 11 is bent and projects downward through a slit of the tubular support. The edges of the slit of the tubular support are bent so that two flaps 12 are formed. The end of rod 11 is pivotably fixed in the side wall of casing 3 by a stud 13. The casing 3 is further connected with the tubular support by a spring 15 which has the tendency to pull the rear part of casing 3 and the plate 1 upward so that the head of the animal is normally lowered.

The tubular support 5 is mounted in the horizontal casing 8 so that it cannot displace itself, for which purpose serve on the one hand the flaps 12 which bear against the neck plate 6 and on the other hand two flaps 10 cut out of the wall of the tubular support and bearing against the rear wall 7 of casing 8. In order to permit that the tubular support can be inserted together with the flaps 17 and 10 from the front end of casing 8 when the toy figure is being put together, openings 25 of convenient size are provided in the end plate 7 of the casing 8 and similar openings 27 in the neck plate 6. The flaps 10 which have originally the same position as the openings are bent up after they have been inserted through the casing 8 as shown on Fig. 4. The flaps 12 are slightly larger and they have another shape or position than the openings 27 so that they cannot engage with these openings as shown on Fig. 5.

The bridles 14 are fixed at the sides of the head at the points 24 above the pivot point 4. The rear end of the tubular support 5 and the lever 19 are enclosed in a stuffed sleeve which forms the tail 16 of the figure.

The toy figure works as follows. If the bridle 14 is pulled simultaneously at both sides the head of the animal is lifted in pivoting around the axle 4 and it moves from the position Fig. 1 into the position Fig. 2. By this movement of the head the spring

- 15 is put under tension so that as soon as the pull on the bridle ceases, the head is brought back to the original position by the action of spring 15. If only the right hand side bridle 5 or the left hand side bridle is being pulled so that this bridle is upwardly inclined, the head turns around the axis of support 5 which revolves in the casing 8. The tail 16 is thus swung to the right or to the left.
- 10 As the front end of rod 11 fixed by stud 13 at some distance from the pivot axle 4 of the head this rod is moved at the lifting and lowering of the head and the tail swings up and down. Inversely the head can be 15 raised and lowered and turned to and fro if the tail is being moved or the lever 19 oscillated. If it is not desired that the head be raised and lowered with the aid of the tail or the tail be swung up and down by raising 20 and lowering of the head the rod 11 and the lever 19 can be suppressed. The tail swings then only in lateral direction if the head is turned but it remains at rest if the head is raised and lowered.
- 25 Instead of the spring 15 a weight or pressure spring can be used and instead of the flexible bridles rigid means could be provided which permit to exert a pressure.
- The invention does not relate only to toy 30 figures the body of which is horizontal but to toy figures of any kind, also to figures which stand upright. The invention relates preferably to toy figures of cloth which are stuffed and which are specially arranged so 35 that they can be fixed upon the tubular support arranged in the body and so that they can be turned in any directions. The invention relates also to solid figures, for instance wooden toy figures in which the head and 40 the tail or only the head are movable.
- I claim:—
1. A toy figure with movable head comprising in combination with the body of the toy figure and with the head of the same, a 45 cup-shaped plate on the lower surface of the head, a cup-shaped plate closing the neck of the body of the toy figure, a casing in the head open at the end which is turned towards the neck, a support for the head rotatably located in the body of the toy figure and projecting into said casing in the head, and a pivot pin oscillatably connecting said casing with said support.
2. A toy figure with movable head comprising in combination with the body of the toy figure and with the head of the same, a cup-shaped plate on the lower surface of the head, a cup-shaped plate closing the neck of the body of the toy figure, a casing
- in the head open at the end which is turned 60 towards the neck, a tubular support for the head rotatably located in the body of the toy figure and projecting into said casing in the head, a pivot pin oscillatably connecting said casing with said support, a means located in said tubular support for moving the head, and a stud for said means hingedly connecting the same with said casing.
3. A toy figure with movable head comprising in combination with the body of the toy figure and with the head of the same, a cup-shaped plate on the lower surface of the head, a cup-shaped plate closing the neck of the body of the toy figure, a casing in the head open at the end which is turned 70 towards the neck, a casing in the body of the toy figure fixed to said neck plate, a tubular support for the head rotatably located in the body of the toy figure and projecting into said casing in the head, a pivot pin oscillatably connecting said casing with said support, and a means for moving the head movably mounted in said tubular support and hingedly connected with said casing in the head.
4. A toy figure of the type described comprising in combination with the body of the toy figure and with the head of the same, a tubular support in said body projecting at both ends from said body, a stud in the head 90 rotatably mounted in the front end of said tubular support, a rod movably mounted in said tubular support, and hingedly connected at its front end with said head, a lever serving as tail of the toy figure oscillatably mounted on the rear end of said tubular support, and a hinge pin pivotally connecting said tail lever with the rear end of said rod.
5. A toy figure of the type described comprising in combination with the body and head of said figure, a tubular support rotatably mounted in said body, means for oscillably mounting the head on the front end of said tubular support, a rod movably located in said tubular support hingedly connected at the front end with said head, a tail hingedly mounted on the rear end of said tubular support and of said movable rod, and a bridle 100 the ends of which are attached at either side of the head.
- In testimony whereof I affix my signature in presence of two witnesses.
